UNITED STATES PATENT OFFICE

121,899

DESIGN FOR A SLIPPER OR SIMILAR ARTICLE

Arthur Iwan, Chicago, Ill., assignor of one-half to Harry F. Ellerman, Chicago, Ill.

Application January 15, 1940, Serial No. 89,470

Term of patent 14 years

To all whom it may concern:

Be it known that I, Arthur Iwan, a citizen of the United States, residing in Chicago, in the county of Cook and State of Illinois, have invented a new, original, and ornamental Design for a Slipper or Similar Article, of which the following is a specification, reference being had to the accompanying drawing, forming a part thereof, in which:

Fig. 1 is a perspective view of a slipper or similar article, showing my new design;

Fig. 2 is a top plan view thereof;

Fig. 3 is a rear elevation thereof, and

Fig. 4 is a front elevation thereof.

I claim:

The ornamental design for a slipper or similar article, as shown.

ARTHUR IWAN.
